UNITED STATES PATENT OFFICE.

STEPHEN HENRY HOWARD, OF TRENTON, TENNESSEE, ASSIGNOR TO J. I. WELLS & SON, OF SAME PLACE.

STEAM-ENGINE.

SPECIFICATION forming part of Letters Patent No. 314,129, dated March 17, 1885.

Application filed August 18, 1884. (No model.)

To all whom it may concern:

Be it known that I, STEPHEN HENRY HOWARD, a citizen of the United States, residing at Trenton, in the county of Gibson and State of Tennessee, have invented new and useful Improvements in Steam-Engines, of which the following is a specification.

The object of my invention is to dispense with the use of the cross-head and slides used in direct-acting steam and other engines, and to produce an engine that will run smoothly at a high speed, and to provide for the taking up of the wear of the pitman-joint connection with the piston.

15 The particular improvement which I have made consists in the combination, with the piston, its guide-trunk, and the pitman-rod, of a piston guide-rod constructed and adapted to secure the piston, the guide-trunk, and the pitman-rod together in a firm and durable manner, the said piston guide-rod serving as the means of clamping the guide-trunk to the piston, the means of connecting the pitman-rod with the piston, and the means, in connection 20 with a screw-bolt carried by said guide-rod, whereby the pitman-boxes are adjusted to take up the wear of its connection with the piston.

Referring to the drawings, Figure 1 represents a horizontal section of an engine adapted to take steam at both ends of the cylinder; Fig. 2, a section of the guide-trunk of the piston; Fig. 3, the piston-head in section; Fig. 4, the pitman-rod in section; Fig. 5, the piston guide-rod and its piston-connections in section, enlarged; Fig. 6, the crank provided with a balance, and Fig. 7 an enlarged sectional detail of the piston, its trunk, and piston-rod connections.

40 The cylinder *a* is adapted, by the usual steam-chest, *e*, and valve connections *f*, with the crank-shaft *g*, to take steam at both ends.

H is the bed-plate upon which the cylinder is mounted.

45 *B* is the piston-head. The piston has guides which pass through each head of the cylinder, one of which guides forms a guide-trunk, *C*, which works through a stuffing-box, *N*, of the inner cylinder-head, the other guide being a 50 rod, *F*, which works through a stuffing-box,

D, of the rear cylinder-head. The pitman-rod *I* connects with the wrist-pin *L* of the crank *M*, and extends into the guide-trunk *C*, the closed end *c* of which has a short neck or nipple, *G*, by which it is clamped against the piston in a manner presently to be stated. The piston-crank connecting-rod has a length about eight times greater than that of the crank, so that there is very little oscillation or side-thrust at the joint-connection within the guide-trunk, 55 and the guide-trunk is of sufficient diameter to allow the pitman-rod to work therein, and has a length sufficient to allow it to work in its stuffing-box in the full stroke of the piston. The guide-rod *F* passes the stuffing-box in 60 the closed end of the cylinder through a central opening in the piston and through a central opening in the closed end of the guide-trunk, and its inner end is forked, and adapted to embrace the enlarged end of the piston-rod *I*, with which it is connected by the joint-pin *R*. By this construction the piston-rod is jointed directly to the guide-rod within the closed end of the guide-trunk. An external screw-thread, *n*, is formed upon the guide- 65 rod to receive a nut, *T*, which being screwed against the piston serves to clamp it firmly 70 against the nipple *G* of the guide-trunk. This clamping function of the guide-rod is effected by a shoulder, *s*, on its divided end, which 75 shoulder, by the action of said screw-nut *T*, bears against the inner side of the closed end of the guide-trunk, as shown in Figs. 5 and 7. This construction gives a firm and durable 80 connection of the piston with its guide-trunk and guide-rod within the cylinder, and a lock-nut may be used with the nut *T* to secure it against working loose, so that the engine will run easy under high speed. The 85 nipple or neck bearing *G* of the guide-trunk 90 serves to expose the piston to the pressure of the steam behind the closed end of the guide-trunk.

The provisions for taking up the wear of the boxes of the piston-rod-joint pin *R* consist in making the piston guide-rod *F* hollow, 95 and providing it with a through-bolt, *P*, the head *Q* whereof lies between the forked ends *F'* of the guide-rod, and bears against one section *a* of the said joint-boxes, the other box- 100

section being secured by a pin, *b*, Fig. 5, passing through the forked ends of the guide-rod. This bolt *P* has a screw-thread, *d*, and the guide-rod has an interior screw-thread, *g*, at 5 its outer end, into which the bolt *P* screws, the end *h* of the latter being made to receive a wrench, by which to turn the bolt when adjustment of the box *a* upon the pipe *R* is necessary. The bolt-head *Q* is cylindrical, and when 10 screwed in jams the box-section *a* upon the joint-pin, and is locked, when adjusted, by a lock-nut, *V*, at its outer end, screwed against the end of the guide-rod. By this means the piston-rod connection with the piston can 15 always be kept tight, and the piston guide-rod utilized as the means of securing the piston-rod, the guide-trunk, and the piston together, while serving to carry the means for taking up the wear at the piston-rod joint *R* from the 20 outside of the cylinder.

An oiling-tube, *J*, on the piston-rod, connects with the piston-joint pin *R*, and, extending outside of the guide-trunk, has a supply-cup, *J'*, which is provided with a screw-cap. 25 The crank *M* may be provided with a balance, *k*, in line with each crank-arm, on the opposite side of the crank, to assist in giving a steady motion to the crank.

I claim—

30 1. The combination, with the piston, of the guide-trunk *C*, having the bearing end *G*, with the piston guide-rod *F*, having the shoulder *s* and the external screw, *n*, the nut *T*, and the

piston-rod, substantially as described, for the purpose specified.

2. The combination with the cylinder and piston, of the guide-trunk *C*, the hollow guide-rod *F*, having an internal screw, the piston-rod, and a screw-bolt carried by said guide-rod, for adjusting the joint-pin bearings of the piston-rod, substantially as described, for the purpose specified.

3. The combination, with the piston and the cylinder of a steam or other engine, of a hollow guide-rod, *F*, having an interior and exterior screw, the guide-trunk *C*, the piston-rod *I*, a screw-bolt, *P*, having a bearing head, *Q*, and an angular end, *h*, and the nuts *V* *T*, substantially as herein set forth.

4. The combination, with the piston, of the guide-trunk *C*, having the closed end *c'*, formed with the bearing projection *G*, the guide-rod *F*, formed with the shoulder *s*, and the screw *n*, and the nut *T*, the said shoulder having a bearing upon the inner side of the closed end 55 of the said guide-trunk, and the said guide-rod having the joint-connection *R* with the piston-rod within the said guide-trunk, as set forth.

In testimony whereof I have hereunto set 60 my hand in the presence of two subscribing witnesses.

STEPHEN HENRY HOWARD.
